UNITED STATES PATENT OFFICE

WILLIS O. PROUTY, OF HERMOSA BEACH, CALIFORNIA, ASSIGNOR TO METLOX CORPORATION, LTD., OF MANHATTAN BEACH, CALIFORNIA, A CORPORATION OF CALIFORNIA

DESIGN FOR A MARQUISE CEILING

Application filed July 24, 1931. Serial No. 40,677. Term of patent 14 years.

To all whom it may concern:

Be it known that I, WILLIS O. PROUTY, a citizen of the United States, and a resident of the city of Hermosa Beach, county of Los Angeles, and State of California, have invented a new, original, and ornamental Design for Marquise Ceiling, of which the following is a specification, reference being had to the accompanying drawings forming part thereof, in which:

ing embodying my invention, a portion being broken away for convenience of illustration;

Fig. 2 is a section thereof substantially along the lines 2—2 of Fig. 1; and

Fig. 3 is a section taken along the plane 3—3 of Fig. 1.

I claim:

The ornamental design for marquise ceiling substantially as shown.

WILLIS O. PROUTY.
